UNITED STATES PATENT OFFICE.

WILLIAM REINHOLD, OF ERIE, PENNSYLVANIA, ASSIGNOR TO BROWN FOLDING MACHINE COMPANY, OF ERIE, PENNSYLVANIA, A CORPORATION OF PENNSYLVANIA.

FOLDING-MACHINE.

1,239,965.

Specification of Letters Patent. Patented Sept. 11, 1917.

Application filed November 2, 1915. Serial No. 59,296.

To all whom it may concern:

Be it known that I, WILLIAM REINHOLD, a citizen of the United States, residing at Erie, in the county of Erie and State of Pennsylvania, have invented new and useful Improvements in Folding-Machines, of which the following is a specification.

This invention relates to folding machines and consists in certain improvements in the construction thereof as will be hereinafter fully described and pointed out in the claims.

One object of the invention is to provide a machine which will fold in proper relation double sheets which have been printed on one form. Other uses of the invention may be had and other objects of the invention will appear from the specification and claims.

The invention is illustrated in the accompanying drawings as follows:

Figure 1 shows one side of a double sheet. Fig. 2 the reverse side of said sheet. Fig. 3 the sheet as slotted. Fig. 4 one part of the slotted sheet. Fig. 5 one part of the slotted sheet after the first fold.

Figs. 6, 7 and 8 the same parts of the sheet carried through successive folds.

Figs. 9, 10, 11, 12 and 13 show views similar to Figs. 4, 5, 6, 7 and 8 with relation to the other part of the sheet.

Fig. 14 a plan view in outline of the machine with the slitting devices.

Fig. 15 a plan view of the reversing rolls and the first folding rolls.

Fig. 16 a view in outline from the left of Fig. 15.

Fig. 17 a view in outline from the bottom of Fig. 15.

Fig. 18 a side elevation of the slitting and reversing rolls and adjacent parts enlarged.

Fig. 19 a view in outline from the left of Fig. 18.

The sheet is shown in Figs. 1 and 2 and after it is slotted as shown in Fig. 3 it forms two parts A and B. One side of the sheet as shown in Fig. 1 has the form 1^a toward one edge and the form 2 toward the opposite edge. The reverse side of the sheet has form 1 opposite the part 1^a and the form 2^a opposite the part 2. In the printed matter on these sheets the inside is formed on 1^a and the outside on 1 and the inside of part A is formed on 2^a and the outside on 2 so that on each surface or face of the sheet

there is an inside part toward one edge and an outside part toward the opposite edge but the entire material is found on the outside and inside surfaces of each piece A and B. This adds to the rapidity of the printing in that this double form may be used and by running the sheets through twice reversing them the entire form is placed on each part of the sheet. The difficulty with this is that one part of the sheet has outside matter on one surface while the other part of the sheet has the outside matter on the other surface. Heretofore these parts have been separated in the printing machine and then reversed and each part fed separately to the folding machine. Other methods may have been used in accomplishing the purpose. With my machine this double form sheet is fed to the machine, slitted, and one part reversed relatively to the other so as to bring the inside portion up on both parts over the first fold rolls.

The sheet is slotted on the line 3 as shown in Fig. 3 and the portion A then passes over the first fold rolls and folded on the line 4^a forming the first fold as shown in Fig. 5. It is then folded on 5^a forming the second fold as shown in Fig. 6; again folded at 6^a forming the third fold as shown in Fig. 7; and is again folded at 7^a forming the completed book or fourth fold as shown in Fig. 8. The part B is folded in a similar manner on the lines 4, 5, 6 and 7 as shown in Figs. 9 to 13 inclusive. One of these parts, as before stated, is reversed before reaching the first fold rolls.

The sheet is fed to the machine on the line 8^a (see Fig. 18) against the stop 8. The stop 8 is carried by an arm 9 on a rock shaft 10. An arm 11 extends from the rock shaft 10 and is operated by a rod 12 from any convenient part of the machine and properly timed to deliver the sheet in the well known manner. The sheet is started by means of the starting rolls 14 and 15. The roll 14 is carried by rock arms 16 mounted on a rock shaft 16^a. A rock arm 17 extends from the rock shaft 16^a and the rod 18 rocks the shaft 16^a, the rod 18 leading to any suitable cam mechanism (not shown) for this purpose. These are timed so that as the stop is lifted the starting rolls operate and feed the sheet forward.

The slitting roll 19 has a slitting groove 20 in which the disk-shaped knife 21 oper-

- ates to slit the paper as it runs past the roll. Tapes 22 are carried around the slitting roll and thus hold the paper in contact therewith and in proper relation thereto to be operated 5 upon by the knife. Tapes 22 extend around the roll 23 above the slitting roll, around idlers 24 and 24^a, the tapes carrying the paper from the slitting roll back under the starting table and over a reversing device.
- 10 As the parts of the paper are carried forward by the tapes 22 they are separated by a separating blade 25 which extends the full length of the sheet, the sheet being arrested by a stop 25^a. This separating blade holds 15 the edges in proper position to be started at the edge by the starting blades hereinafter described and merges into the guide by which the sheets are guided between the reversing rolls 28 and 29 hereinafter described.
- 20 The reversing device is as follows: The reversing rolls 28 and 29 are arranged immediately under and parallel with the slitted edge of the sheet as it is carried against the stop 25^a. The blade 25 is carried by a guide 25. The guide 26 is carried by a rod 27 mounted in any convenient manner. The guide 26 extends between the reversing rolls 28 and 29. Starting blades 30 and 31 are arranged each side of the blade 25. They 30 have the upward projections 32 and 33 which are attached to a bar 34. The bar 34 is carried by the rock arms 35. The rock arms 35 are mounted on the rock shaft 36. The rock arm 37 is mounted on the rock shaft 36 and is connected by a link 38 with a rock arm 39. The rock arm 39 is mounted on a shaft 40. A rock arm 41 extends from the shaft 40. A rod 42 extends from the rock arm 41 and has a slotted end 43 which is arranged 40 around a cam shaft 44. A cam roller 45 is arranged on the slotted end 43 and is adapted to drop into a depression 46. A spring 42^a is mounted on the rod 42 and when the cam roller 45 drops into the cam depression 46 45 the spring and the weight of the parts through the chain of mechanism depresses the bar 34 thus moving the starting blades 30 and 31 downwardly bending the edges of the sheets into the bite of the reversing rolls 50 28 and 29.
- The starting rollers 48 and 49 are arranged above the reversing rolls 28 and 29 and are adapted to drop into contact with the sheets just after the edges are deflected 55 so as to start the sheets past the reversing rolls. The roll 48 is carried by the rock arms 50. The rock arms 50 have the shaft 51. The rock arm 52 extends from the shaft 51 and is connected by a rod 53 with the slotted end 54 arranged on the cam shaft 44. A cam roller 55 is adapted to drop into the cam depression 56. A spring 57 is arranged 60 on the rod 53 and it and the weight of the parts depresses the roll 48 when the roller 55 drops into the cam slot 56. The roller

49 is carried by rock arms 58. The rock arms 58 are carried by the rock shaft 59. A rock arm 60 is mounted on the shaft 59 and connected by a rod 61 with the rock arm 52 so that as the rock arm 52 is rocked to drop the roll 48 it rocks the arm 60 and thus drops the roll 49 into feeding relation.

The sheets are carried over the rolls 28 and 29, as shown in Fig. 15. The portion A is carried around the roll 29, the edge being 75 deflected by the guide plate 26 and carried on to the tapes 62, the tapes 62 being operated by the roll 63. The sheet as it is carried around the roll 29 is reversed upon itself bringing the inside 1^a to the top and the portion A is then delivered over the first fold rolls 64 (see Fig. 15) by the tapes 62. From this it is carried in the well-known manner of folding machines through the rolls 65, 66 and 67.

The part B of the sheet is carried around the roll 28 and delivered between the guide plates 68 to the intermediate rolls 69. It is deflected as it passes the rolls 69 by a deflector 68^a carried by one of the guide plates 68 between the guide plates 70 and delivered from the guide plates 70 under the roll 71 and onto tapes 72, the tapes being carried by the roll 73. The sheet is carried by the tapes 72 which extend under the tapes 62 95 over the first fold rolls 73 for the portion B, these rolls for convenience being directly under the rolls 64. It will be observed that this part B will be delivered over the first fold rolls with the same side up, namely the 100 inside or 2^a up, when the portion is on the tapes 72. The sheet is then folded through the successive rolls 74, 75 and 76.

With this mechanism, therefore, it will be seen that a single double form may be used 105 running the paper twice and this double sheet is split and one portion reversed so that both portions may be properly folded starting with the fold toward the inside.

What I claim as new is:—

1. In a paper folding machine, the combination of a slitting device; reversing means comprising reversing rolls parallel with the cutting line of the slitting device; conveying mechanism for carrying the slitted sheet 115 from said slitting device to the reversing rolls; starters carrying the slitted edges of the sheets into the reversing rolls; a set of folding rolls for each part of the slitted sheet; and conveying means extending from 120 the reversing rolls carrying both parts of the sheet to their respective folding rolls, one part to each set and reversing one part relatively to the other.

2. In a paper folding machine, the combination of a slitting device; reversing mechanism comprising reversing rolls parallel with the slitting device; conveying mechanism for carrying the slitted parts of the sheets to the reversing rolls; a set of fold- 125

ing rolls for each part of the sheet, one set being above the other; and conveying means extending from said reversing rolls for carrying both parts of the slitted sheet to their respective folding rolls, one part to each set of folding rolls, said conveying means turning one part of the sheet back upon itself and into position over one set of the folding rolls and the second part of the sheet without reversing, said latter part to folding position over the other set of folding rolls.

3. In a paper folding machine, the combination of reversing rolls; means for carrying two sheets of paper into position above said rolls with their edges adjacent and parallel to the axis of said rolls; a starting device acting on the edges of said sheets for starting said sheets through said rolls; a folding device for each sheet; and conveying means for carrying the sheets from said reversing rolls to said folding devices, one sheet to each folding device, said conveying means reversing one of said sheets upon itself as it is conveyed to folding position over one set of folding devices and convey-

ing the second sheet without reversing to folding position over the other folding device.

4. In a paper folding machine, the combination of a pair of reversing rolls; a separating plate extending parallel to the bite of said rolls; starting blades at each side of said plate; a bar to which said blades are attached; and means for actuating said bar.

5. In a paper folding machine, the combination of a pair of reversing rolls; means for feeding two sheets of paper with their edges adjacent and parallel to the bite of said rolls; a starting device for starting the edges of said sheet into said reversing rolls; 40 tapes for carrying the first of said sheets back under itself and reversing the sheet; a guide way for carrying the second of the sheets downwardly to intermediate rolls; 45 said intermediate rolls; guides extending from the intermediate rolls to a horizontal carrying means; and a horizontal carrier.

In testimony whereof I have hereunto set my hand.

WILLIAM REINHOLD.
